CIGAR LIGHTER

Joseph H. Cohen, Bridgeport, Conn., assignor to
 Automatic Devices Corporation, Bridgeport,
 Conn., a corporation of Connecticut

Application June 21, 1939, Serial No. 280,270

10 Claims.

(Cl. 219—32)

This invention relates to cigar lighters, and, more particularly, to a holder for removably supporting an igniting unit carrying a heating element, and is an improvement over the invention disclosed and claimed in my prior application, Serial No. 93,770, filed August 1, 1936, now Patent No. 2,210,025, issued August 6, 1940.

While the invention, in its broader aspects, is not limited to automatically controlled cigar lighters of the type wherein the igniting unit is completely removed from the holding device for use, the present invention has special utility and advantage when used in such a device.

It has been heretofore proposed to employ with such automatically controlled cigar lighters a means for permanently breaking the circuit to the heating element if the same should become overheated due to failure of the usual circuit-breaking means to operate or if a short circuit should occur in the igniting unit circuit. These prior proposed means have usually consisted of a fusible element generally made a part of the heating element circuit fusible upon a sudden surge of current or have been placed in heat-receiving relation to the heating element so that the same would, upon the heating element attaining some dangerous temperature, fuse and thereby break the circuit to the heating element. In these prior proposed constructions, the fusible element, if replaceable at all, could be replaced only after the removable igniting unit or holding device had been disassembled to allow access to the fusible element.

It is an object of the present invention to provide a device which will permanently open the circuit if the heating element should attain some dangerous heat or if a short circuit should occur and which device when destroyed can be easily replaced without necessitating the partial disassembly of either the igniting unit or the holding device.

The device, according to the present invention, is made attachable to the holding device and forms a part of the circuit of the heating element, and as well, is in close heat-exchanging relation with the heating element. The device includes a thermoplastic element so made a part of the device that should the heating element attain a dangerous heat or should a short circuit occur which might cause an overload of the heating element, the element allows the circuit to be permanently opened.

The element normally holds a pair of contacts in closed-circuit position but which when softened or destroyed is no longer operative to hold

the contacts in such position, and the circuit is permanently opened. The device, after the element has been destroyed, may be very quickly and easily replaced by a similar device without removing either the holding device from its support or removing the igniting unit from the holding device.

Other features and advantages will hereinafter appear.

10 In the accompanying drawing: Figure 1 is a longitudinal sectional view of the device of the present invention showing the igniting unit in the closed-circuit position and the fusible element in its normal position.

15 Fig. 2 is a sectional view partly in elevation showing the igniting unit in the circuit-closing position, but showing the condition of the fuse and the position of the circuit-breaking members after the fuse has become softened.

20 Fig. 3 is an exploded view showing the various elements of the fuse assembly.

25 Fig. 4 is a sectional view of the fuse assembly showing a different means of connecting the current-supply wire to the same.

Fig. 5 is a view similar to Fig. 4, but showing a still modified means of attaching the current-supply wire to the same.

30 Fig. 6 is an elevational view of the wafer-carrying cartridge.

35 As shown in the drawing, the present invention is applied to an automatic lighter of the type in which the igniting unit is completely removed from the holding device for use.

In the particular lighter illustrated, the holding device comprises a well or socket 10 adapted to be mounted in an aperture in an instrument board 11 of an automobile or the like with a flange 12 of the socket in engagement with the front face of the instrument board. The well is secured in place by a tubular shell 13 having a nipple 14 threaded over a boss 15 carried by a transverse wall 16 of the socket 10.

40 The igniting unit may be a generally cylindrical member having a sliding fit within the cylindrical shell 10. In the form of the invention as herein shown, the igniting unit comprises a body portion made up of a dielectric sleeve 17 threaded into a knob member 18 of some suitable insulating material. The inner end of the igniting unit is provided with a heating element 19 comprising a spiral coil of resistance wire 20 mounted in a cup 21 to which the outer end of the wire is secured, the inner end of the wire being secured to a post 22.

45 The heating element, in the form shown, is re-

movably mounted on the igniting unit, the end of the latter being provided with threads 23 to receive a screw threaded cap 24 secured to the cup 21 by peening over a head 25 of the post 22. The post carries between the cup 21 and the threaded cap 24 an insulating washer 26.

The igniting unit is adapted to be held in shallow open-circuit position on the holding device by means of a spring 27 carried by the igniting unit and engaging a flange 28 formed at the inner end of a sleeve 29. The sleeve 29 at the forward end has a flange 30 engaging the flange 12 of the holding device, so that when the igniting unit is pushed into a deep position in the holder, the spring is compressed.

The spring 27, as shown, is disposed within an annular groove formed in the sleeve 17 and is placed in front of the handle 18 with one end thereof engaging the flange 28 and the sleeve 29. A ring 31 is secured to the sleeve 17 and is engaged by the opposite end of the spring and will prevent the spring from separating from the sleeve 17 should the handle 18, for any purpose, be removed. The sleeve 29 is disposed so as to be movable lengthwise relative to the sleeve 17 and the cap 24 is connected thereto to enable the unit to be moved into a deep circuit-closing position.

A plurality of light-transmitting apertures 32 are formed in the transverse wall of the cup 21, insulating washers and transverse wall of the cap 24, so that when the heating element reaches incandescence, light will be transmitted through the apertures, the bore of the sleeve 17 to the hollow handle 18 which is provided with a lens 33 of some suitable material which will be caused to glow and indicate to the user that the heating element has reached incandescence.

To complete a circuit to the heating element when the igniting unit is moved to a deep position in the holding device, a cooperating contact means is carried by the rear or transverse wall of the holding device.

In the broader aspects of this invention, any suitable form of mounting means for the contacts of the holding device may be employed. In the form of the invention illustrated, however, the contacts of the holding device are supported by an insulating block 34. This insulating block is provided with a central recess to house a disk 35 having a plurality of radially extending contact fingers 36. The block 34 also is provided with a plurality of spaced apertures 37 radiating from the central recess to receive a second disk 38 provided with a plurality of radially extending contact fingers 39. A stud 40 holds all the members together, the stud having a head 41 overlying the disk 35 carrying the contact fingers 36 and underlying the disk 38 carrying the contact fingers 39.

The head of the stud has a reduced portion extending through an aperture in the disk 35 and is spun or riveted over to permanently unite the contact fingers thereto. As thus assembled, the stud and the plurality of disks carrying the contact fingers are locked to and on the insulating member 34. The stud 40, with an insulating sleeve 42 and a washer 43, extends rearwardly through an aperture formed in the rear wall of the holding device and projects beyond the same. A reinforcing member 44 is disposed between the insulating body 34 and the rear wall of the holding device. The stud 40 is provided with a threaded end portion receiving a nut 45 and a washer 46 to insulate the nut 45 from a second

reinforcing member 47. When the nut 45 is tightened, the contact assembly is securely clamped to the rear or transverse wall of the holding device as a unit.

5 The stud 40 is adapted to be connected to a source of current such as the usual storage battery so that current may be conducted to the heating element when the igniting unit is moved against the action of the spring 27 to a position 10 wherein the contact fingers 39 engage the cup 21. The coil 20 of the heating element, as it is connected to the stud 22 which is carried by the cap 24, will complete the circuit to ground through the holding device 18 by means of a finger 48 lanced from the wall of the holding device 18 and in engagement with a flange 49 of the cap 24.

The fingers 39 are resilient and are preferably constructed of some bimetallic material. 20 As shown, they have the ends thereof offset so as to extend substantially normal to the disk 38. The ends of the fingers are cammed apart when the cup contacts the same and are also provided, preferably, with depressed portions 49 adapted to engage and receive the rim of the cup when the igniting unit is moved to its deep operative position. The resiliency of the fingers 39 is such that they grip and retain the igniting unit against return movement under the influence of the spring 27 until the heating element has been brought to a predetermined temperature for use. While the heating element is being energized, the heat therefrom is conducted to the fingers 39 through the cup 21, 30 and, due to their construction of some bimetallic material, will flex so that they release the cup. When the fingers release their engagement with the rim of the cup 21, the spring 27 is then free to return the igniting unit to the shallow inoperative position, breaking the circuit to the heating element.

If it is desired to reenergize the heating element and the fingers 39 have not cooled sufficiently to allow them to return to their normal 45 position, the igniting unit may be again moved inwardly until the cup is brought into engagement with the fingers 39 and held manually in that position until the heating element has reached its desired incandescence. The user will 50 be apprised of the incandescence of the heating element for, as previously explained, light from the incandescent element will be transmitted through the apertures 32, bore of the sleeve 17 to the lens 33 of the handle 18.

55 There is very little likelihood of the bimetallic fingers 39, if the device is properly used, failing to flex and allowing the igniting unit to be returned by the spring to the shallow circuit-opening position; nevertheless, due to abuse, such as excessive, improper use or natural fatigue of the parts after having been used over a long period of time, there is a possibility of such a failure. If such a failure should occur, it will 60 be understood that the heating element can reach a dangerous heat which can cause the destruction of the entire device.

To prevent the destruction of the entire device, should the bimetallic fingers 39 fail to respond properly and release the igniting unit, the present invention provides a means for permanently opening the circuit to the heating element after the heating element has reached a temperature higher than the one necessary, but yet lower than a dangerous heat which might 70 cause a destruction of the device.

This means, in the present invention, comprises a pair of contacts held in normal circuit closed position by means of a thermoplastic member which will soften at some critical predetermined temperature, less than a dangerous one, to allow a spring associated with one of the contacts to move that contact out of engagement with the other to the end that the circuit to the heating element will be opened.

The means for preventing the heating element from reaching a dangerous heat comprises a removable assembly which is connected into the circuit leading into the heating element. The stud 40, by means of which the contact assembly is securely clamped to the rear wall of the holding device, is of a length to project rearwardly a distance sufficient to take a threaded sleeve 50. The sleeve 50 terminates in a reduced portion which carries a disk 51 of some suitable insulating material. The disk 51 is held against separation from the sleeve as the end of the latter is peened or riveted over to form a retaining head 52 which clamps the disk against the shoulder 53 of the sleeve 50. A coil spring 54 seating on the disk urges a metallic disk 55 rearwardly and away from engagement with the head 52 of the sleeve 50. The disk 55 is provided on the rear face thereof with a cup-like member 56 secured to the rear face in any suitable manner, but herein shown as having a friction fit in a centrally located recess formed in the disk 55. The cup-like member may be of any suitable shape desired, and, as herein shown, is frusto-conical. The cup projects rearwardly of the disk 55 and engages a circular wafer of some thermoplastic material enclosed within a cartridge 57a of brass or the like. The cartridge 57a, as clearly shown in Fig. 6, is provided on the face engaged by the cup-like member 56 with a plurality of fingers 58 projecting centrally of the same but terminating just short of the center thereof.

To hold the spring disk and cartridge in the position desired, a sleeve 59 of insulating material is slipped over the same until the one end thereof engages the disk 51. A cylindrical housing 60 having a transverse wall formed at one end thereof by an insulating disk 61 is slipped over the sleeve 59 and securely clamped to the disk 51 by a plurality of fingers 62 which are bent over to engage the outer face of the disk 51 which forms a closing transverse wall for the housing 60. The insulating disk 61 carries a centrally located stud 63 carrying at the inner end a spider 64 provided with a plurality of resilient fingers 65 which engage the rear face of the cartridge 57a. The spider 64 is secured to the inner face of the disk 61 by heading over the end of the stud 63. The stud 63 is provided with an integral stop collar 66 which engages the outer face of the disk 61 and cooperates with the head of the stud to hold the disk 61 and spider 64 against relative movement. The outer end of the stud 63 is threaded to take a nut 67 to clamp a contact clip 68 against the collar 66. A conductor wire 69, connected to the usual storage battery of the vehicle, is secured to the clip.

It will be seen that when the various elements enclosed by the housing 60 are in their assembled position, the disk 55 will be in engagement with the peened over portion of the sleeve 50 and that the cup-shaped member 56 will engage the fingers 58 of the cartridge 57a as the resilient fingers 65 of the disk 64 will urge the cartridge and the disk 55 to the right as viewed in Figs. 1 and

2. The resiliency of the fingers 65 is such that they offset any tendency of the coil spring 54 to urge the disk 55 away from the head 52 of the sleeve 50 against which the disk 55 abuts.

5. It will be seen that the current will be conducted to the heating element when the igniting unit is moved inwardly against the action of the spring 27 to a position where the contact fingers 39 engage the cup 21 as a circuit will be established from the conductor 69, stud 63, spider 64, cartridge 57a, cup member 56, disk 55, sleeve 50, stud 40, disk 38, fingers 39, cup 21 to the coil 20 which, as previously explained, is grounded through cap 24 to the finger 48 lanced from the wall of the holding device 10.

10. The heat of the energized heating element, as previously explained, will cause the bimetallic fingers 39 to flex or move away from the cup 21, whereupon the igniting unit is moved by the spring 27 to the shallow position breaking the circuit through the heating element. If, however, for some reason the fingers 39 fail to respond properly and the circuit through the heating element is maintained for a period longer than is necessary to bring the heating element to the desired temperature, the likelihood of a dangerous condition arising has been completely obviated by the present invention. Should the fingers 39 fail to function and retain the igniting unit in the energizing position, after the heating element has reached its desired heat, the stud 40 will transmit heat to the sleeve 50, disk 55 and cup-shaped member 56 which is, as has been explained, in contact with the cartridge 57a housing the fusible wafer 57. If sufficient heat is conducted to the wafer and the same softens, the spring 54 will urge the disk 55 and cup-like member 56 rearwardly, and, as the fingers 58 of the cartridge 57a are free to bend back into the body of the wafer, the same, upon softening of the wafer, as shown in Fig. 2, will do so and the disk 55 under the action of the spring 54 will be moved out of engagement with the headed over portion of the sleeve 50. The separation of the disk 55 from the sleeve 50 will break the circuit to the igniting unit and prevent the heating element from reaching any dangerous degree of temperature.

The wafer of thermoplastic material may be made up from some suitable low melting point metal, but, preferably, it is made of some non-conducting material such as a high melting point wax. If a metal was used to form the wafer, there is a possibility that the same, when it has softened or melted, will close the circuit by bridging other portions of the same.

The cartridge 57a, as it is connected in series with the heating element, is of a size to safely carry the current required by the coil 20 during its normal use, but should the current, passing through the circuit, be materially increased as from a short circuit in the coils of the heating element or for other reasons, the cartridge will become heated causing the wafer to soften allowing the cup member under the action of the spring 54 to pierce the wafer, and any danger to the device will be obviated, as previously explained.

It will be understood that the melting point of the material used to form the wafer is such that the same will melt before the heating element reaches a dangerous degree of temperature. The fuse assembly may be very quickly replaced if the same should be destroyed by merely removing the nut 67 from the stud 63 and unscrew-

ing the sleeve 59 from the threaded end of the stud 40. A new fuse assembly can be substituted for the destroyed one by merely threading the sleeve 50 of the new assembly onto the stud 40 and securing the conductor wire 50 to the stud 63 by the nut 67.

To facilitate the attachment of the contact clip to the threaded stud 63, the studs shown in Figs. 4 and 5 can be substituted. If the stud 70 of Fig. 4 is used, a connector sleeve 71 having a flanged end clamped between the flange 72 of the housing 60 and the disk 61 is provided with suitable lugs 73 which are adapted to cooperate with a second connector sleeve, not shown, which is carried by the conductor wire leading from the source of current.

The stud 74 of Fig. 5 is provided at the end with a perimetrical groove 75 which is adapted to be snapped under a suitable circular spring, not shown, carried by the conductor wire, which, as will be seen, will complete a Bronson type terminal or connection with the conductor wire leading from the source of current.

It will be appreciated that any type of connection might be employed to connect either side of the fuse assembly to the conductor wire on the one side and the stud 40 on the other.

Variations and modifications may be made within the scope of this invention and portions of the improvements may be used without others.

I claim:

1. A holding device for an igniting unit of an electric cigar lighter having a heat-conducting current carrying stud projecting from the rear wall thereof; and a manually removable switch means carried by the projecting end of said stud and accessible without disassembling said holder or igniting unit, said switch means including a contact electrically connected to the end of said stud, a movable contact, means for connecting said movable contact to a source of current, resilient means for holding said movable contact out of engagement with the contact connected to said stud, and thermoplastic means for holding said movable contact in engagement with the contact means on the stud against the action of the resilient means but becoming plastic at a temperature higher than one predetermined and allowing said resilient means to separate the contacts.

2. A holding device for supporting a removable igniting unit carrying a heating element; an electric circuit for energizing said heating element upon movement of at least a part of the igniting unit to a deep position on said holding device; and means forming a part of said circuit and exteriorly carried by said holding device for normally closing but permanently opening said circuit if the same is held closed for a time sufficient to cause the heating element to reach a dangerous temperature, said means being easily accessible and manually replaceable by a like means without disassembly of either holding device or igniting unit after the means has permanently opened said circuit for again closing the circuit.

3. A holding device for supporting a removable igniting unit carrying a heating element; a contact disposed within the holding device and adapted to be engaged by a contact carried by the igniting unit upon movement of at least a part of said igniting unit on the holding device to a circuit-closing position on said holding device to energize said heating element; a switch carried exteriorly of said holding device; thermoplastic means for holding the switch closed and

for releasing the switch to open-circuit position upon becoming plastic; and means including means for mounting said contact to said holding device and said switch exteriorly thereof for transmitting heat from the heating element to the thermoplastic means whereby overheating of the heating element will soften said thermoplastic means and open the switch.

4. A holder for supporting a removable igniting unit carrying a heating element; a contact disposed within said holder and adapted to be engaged by a contact carried by the igniting unit for closing an energizing circuit for the heating element when the igniting unit is moved to a closed-circuit position on said holder; means for securing said contact on the holder including means extending exteriorly of the holder; said means being current conducting and forming a part of said circuit; and means for connecting said extending means to a source of current including fusible means for opening said circuit should the heating element attain a temperature higher than one predetermined, the securing means being heat conducting and providing a direct heat path from said heating element to said fusible means.

5. A holder for supporting a removable igniting unit carrying a heating element; a contact on said holder for engagement with a contact on said igniting unit for completing an energizing circuit through said heating element; means for securing the contact on the holder including a heat-conducting metal stud, a part of which projects exteriorly of the holder; means for connecting said stud to a source of current including a normally closed thermoplastic switch means removably carried by the projecting part of said stud and included in said energizing circuit for opening said circuit should the heating element attain a temperature higher than one predetermined.

6. A holder supporting a removable igniting unit carrying a heating element having an electrical contact surface; a contact carried by a transverse end closing wall of said holder adapted to be engaged by said contact surface when the igniting unit is moved to a deep position on said holder; means for securing said holder contact to the transverse wall including a current-conducting metal stud, a part of which is projected beyond the holder; means removably carried by the projecting end of said stud for connecting the stud to a source of current including a normally closed switch; and means operative to permanently open the switch upon the stud conducting heat thereto of a temperature higher than one predetermined.

7. A holder for a removable igniting unit of an electric cigar lighter carrying a heating element having a contact surface; a contact carried by an end wall of said holder adapted to be engaged by the contact surface of said igniting unit when the same is moved to a deep position on said holder; means for securing said holder contact on the wall including a current-conducting metal stud, a part of which passes through said wall; a contact carried by the projecting end of said stud; a second contact connected to a source of current; means normally tending to separate said contacts; and a thermoplastic means holding said contacts in good electrical engagement until the heating element attains a heat higher than one predetermined; said stud providing a direct heat path between the heating element and said thermoplastic means.

8. A holder having a transverse wall formed at one end thereof for supporting a removable igniting unit carrying a heating element having a contact surface; a thermoresponsive contact disposed on said transverse wall and engageable with the contact of said unit to close a circuit through said heating element when at least a part of the igniting unit is moved toward said transverse wall, said thermoresponsive contact impositively gripping the contact surface of the heating element to hold said circuit closed for a predetermined time; thermoplastic switch means carried on the opposite side of said transverse wall; and a common conductor support providing a direct heat path from said heating element to said thermoplastic switch means for securing the thermoresponsive contact and thermoplastic switch means to opposite sides of said transverse wall, the thermoresponsive contact operative upon the heating element reaching a predetermined useful temperature to move out of engagement with the contact carried by the igniting unit to automatically open the circuit, the thermoplastic switch means operative upon the heating element attaining a temperature higher than the said predetermined one for permanently opening said circuit.

9. A holder supporting a removable igniting unit carrying a heating element; a contact disposed within said holder adapted to be engaged by a contact carried by the igniting unit for closing a normally open energizing circuit for the heating element when the igniting unit is moved to closed-circuit position on said holder; means for securing said contact to a transverse wall of the holder including a current-conducting threaded metal stud extending through said wall; and manually replaceable means for removably connecting said stud to a source of current including a metal sleeve having a thread engaging

said extending part of the stud, a housing carried by said sleeve, switch means carried within said housing, said switch means including the sleeve, a movable contact connected to an electrical source, resilient means carried within the housing for urging said movable contact away from said sleeve, and thermoplastic means carried by said housing for normally holding said movable contact in engagement with said sleeve against the urging of said resilient means, the thermoplastic means adapted to become plastic upon the heating element attaining a degree of heat higher than one predetermined and inoperative to hold said movable contact in engagement with said sleeve against the urging of said resilient means for permanently opening the circuit.

10. A holding device for a removable igniting unit carrying a heating element; a contact carried by the holding device for cooperation with a contact on the igniting unit, the holding device contact being disposed on a transverse closing wall and insulated from the holding device; an elongate heat-conducting current carrying stud securing said last-named contact to the transverse wall, said stud being insulatedly carried by said end wall and projecting through the same; a contact carried by the projecting end of said stud; a movable contact; resilient means urging said movable contact to a position out of engagement with the contact carried by the projecting end of the stud; and thermoplastic means holding said movable contact in good electrical engagement with the stud contact, said thermoplastic means adapted to become plastic upon the heating element attaining a degree of heat higher than one predetermined and inoperative to hold said movable contact in engagement with said stud contact.
